UNITED STATES PATENT OFFICE.

CARL JAEGER, OF MINNEAPOLIS, MINNESOTA, ASSIGNOR OF ONE-HALF TO WILLIAM T. FRANKLIN, OF ST. PAUL, MINNESOTA, ONE-EIGHTH TO A. G. WALTER, OF ST. PAUL, MINNESOTA, AND ONE-TENTH TO WILHELMINA MARIE ERICKSON, OF MINNEAPOLIS, MINNESOTA.

MECHANICAL REFRIGERATOR.

Application filed June 21, 1919. Serial No. 305,802.

To all whom it may concern:

Be it known that I, CARL JAEGER, a citizen of the United States, residing at Minneapolis, in the county of Hennepin and State of Minnesota, have invented certain new and useful Improvements in Mechanical Refrigerators; and I do hereby declare the following to be a full, clear, and exact description of the invention, such as will enable others skilled in the art to which it appertains to make and use the same.

My invention relates to refrigeration and has for its special object the provision of an extremely simple and highly efficient mechanical refrigerator particularly adapted for domestic use, but capable of being made in various sizes and used generally, for maintaining low temperatures. Generally stated, the invention consists of the novel devices and combinations of devices hereinafter described and defined in the claims.

In the accompanying drawings which illustrate the invention, like characters indicate like parts throughout the several views.

25 Referring to the drawings:

Fig. 1 is a plan view of the improved refrigerator, some parts being broken away;

Fig. 2 is a side elevation of the compressor, some parts being sectioned;

30 Fig. 3 is a plan view of the condensers or refrigerators; and

Fig. 4 is a section taken approximately on the line 4—4 of Fig. 1, but with some parts in full elevation.

35 The case or housing of the refrigerator is indicated by the numeral 5, and the numeral 6 indicates what usually corresponds to an ice box, but which in this arrangement contains a so-called refrigerator. Here it may be stated that in this refrigerating apparatus, the radiator, which is located in the atmosphere outside of the refrigerator casing is of a construction very similar to that of the refrigerator which is located within the 40 so-called ice compartment. The construction of the so-called refrigerator will first be described, as follows.

The head or top portion of the refriger-

ator 7 is formed with a lower compartment 7^a and an upper compartment 7^b separated by a horizontal partition 7^c. A plurality of outer tubes 8 are connected to and depend from the heads 7, being, as shown, screw-threaded into the bottom plate thereof, and in free open communication with the compartment 7^a. These tubes 8 may vary in number, according to the required refrigerating capacity, but, as shown, there are four of such tubes in rectangular disposition. Relatively small pipes or tubes 9 are tapped through the partition 7^c and lead from the upper compartment 7^b down through the respective tubes 8 and terminate close to the bottoms thereof. As shown, the lower ends of the tubes 8 are closed by detachable heads 8^a. Inasmuch as the construction of the so-called radiator and the refrigerator, in so far as the latter has been so far described, are identical, the same or corresponding parts are indicated by the same numerals or identifying characters.

Located on top of the casing 5 is a compressor indicated as an entirety by the numeral 10, the same being of the rotary type, and which may, therefore, be briefly described, as follows:

Reciprocating pump pistons 11 working in cylinders 12 produce partial vacuum in chamber 10^a and force the vapor into compartment 10^b where it is condensed into liquid form in a well known manner. Pistons 11 are driven through piston rods 13, a wobbling head 14 and a crank, not shown, but which latter is carried by a shaft 15 equipped with a pulley 16. Also, on top of the casing 5 is a small electric motor 17, the armature shaft of which is equipped with a pulley 18. A belt 19 runs over the pulleys 18 and 16 to operate the compressor in a well known manner. The motor may be automatically controlled through thermostat and controlling circuit, or otherwise, so far as this invention is concerned.

From the compression chamber 10^b of the compressor, a pipe 20 extends to the lower chamber 7^a of the radiator. This pipe 20 is

shown as provided with a normally open valve 20^a. From the upper compartment 7^b of the radiator, a pipe 21 extends to the compartment 7^b of the refrigerator. This pipe 21 is shown as provided with a normally open valve 21^a by means of which the rate of flow of the liquid from the radiator to the refrigerator may be varied.

A pipe 22 extends from the lower compartment 7^a of the refrigerator to the vacuum or suction chamber 10^a of the compressor. This pipe 22 is also shown as provided with a normally open valve 22^a. The numeral 23 indicates a pressure gage applied to pipe 21. The numeral 24 indicates a pressure gage applied to pipe 22.

In the freezing of ice in cakes, small metallic pans are provided and these are adapted to be held between the tubes 8 of the refrigerator, by means of supporting lugs 26 applied to the tubes 8 thereof, as shown in Fig. 4. As the circulating refrigerating medium, I employ a volatile liquid consisting preferably of about eighty-five per cent of sulphurous acid and fifteen per cent of carbonic acid. This fluid, when about fourteen degrees above zero, Fahr., under compression higher than atmospheric pressure, will be in gaseous or vapor form, and from the chamber 10^b will be forced through pipe 20, first to lower compartment 7^a of the radiator upper compartment 7^b. In passing through the tubes of the radiator, the liquid, which, by this compression has absorbed heat, will be cooled, and from thence, will pass through pipe 21 to upper compartment 7^b of the refrigerator, and from thence, through the plurality of small tubes 9. As the liquid under compression is discharged from the lower ends of the small tubes 9 into the relatively large tubes 8, it will be released and permitted to rapidly expand, thereby rapidly absorbing heat from the interior of the ice box or refrigerator casing 9, or, in other words, producing the required low temperature therein. These relatively small and large tubes of the radiator, therefore, act as expansion valves or devices that make unnecessary the use of the ordinary expansion valves, and moreover, the several sets of tubes act simultaneously or in unison, so that intense cold will be produced. The expanded vapors will be drawn from the refrigerator back to the suction chamber 10^a of the compressor, through pipe 22. In this way, by extremely simple and efficient means, a highly efficient low cost refrigerating apparatus is provided.

60 The efficiency of this device has been demonstrated in actual practice.

What I claim is:

1. A refrigerating device comprising a head having two chambers, relatively large tubes projecting from one of said cham-

bers, relatively very small tubes extended from the other chamber through said relatively large tubes and terminating near the ends thereof, and ice pans detachably supported by and located between the said refrigerating tubes.

2. A refrigerating device comprising a head having two chambers, relatively large tubes projecting from one of said chambers, and relatively very small tubes extended from the other chamber through said relatively large tubes and terminating near the ends thereof, the said refrigerating tubes being in rectangular arrangement and having lugs on their opposing sides for, detachably supporting ice pans.

3. In a refrigerating apparatus, the combination with a casing, of a refrigerator within said casing and a radiator outside of said casing, said refrigerator and radiator each comprising a head with upper and lower compartments, relatively large tubes depending from said lower compartments, relatively very small tubes extended from the upper compartments and downward into the corresponding relatively large tubes; a compressor, a pipe connecting said compressor to the lower chamber of said radiator, a pipe connecting the upper chamber of said radiator to the upper chamber of said refrigerator, and a pipe connecting the lower chamber of said refrigerator to said compressor.

4. In a refrigerating apparatus, the combination with a casing, of a refrigerator within said casing and a radiator outside of said casing, said refrigerator and radiator each comprising a head with upper and lower compartments, relatively large tubes depending from said lower compartments, relatively very small tubes extended from the upper compartments and downward into the corresponding relatively large tubes, a compressor, a pipe connecting said compressor to the lower chamber of said radiator, a pipe connecting the upper chamber of said radiator to the upper chamber of said refrigerator, and a pipe connecting the lower chamber of said refrigerator to said compressor, the pipe connecting said radiator to said refrigerator having a valve for controlling the rate of flow therethrough.

5. In a refrigerating apparatus, the combination with a casing, of a refrigerator within said casing and a radiator outside of said casing, said refrigerator and radiator each comprising a head with upper and lower compartments, relatively large tubes depending from said lower compartments, relatively very small tubes extended from the upper compartments and downward into the corresponding relatively large tubes; a compressor, a pipe connecting said compressor to the lower chamber of

said radiator, a pipe connecting the upper chamber of said radiator to the upper chamber of said refrigerator, a pipe connecting the lower chamber of said refrigerator to said compressor, and an electric motor with connections for driving said compressor.

In testimony whereof I affix my signature in presence of two witnesses.

CARL JAEGER.
